ATTORNEYS

UNITED STATES PATENT OFFICE.

JOHN O. McKEAN, OF WESTFIELD, MASSACHUSETTS.

COP CONE.

Application filed December 27, 1922. Serial No. 609,295.

To all whom it may concern:

Be it known that I, JOHN O. McKEAN, a citizen of the United States, and resident of Westfield, in the county of Hampden and State of Massachusetts, have invented a new and useful Improvement in Cop Cones, of which the following is a specification.

The winding surfaces of cop cones, especially when the cones are made of paper, are at times irregular. This is caused frequently by the walls of the cones being thicker at certain points than at others, or by the warping of the walls of the cones in the drying out process after the cones are made. These irregular cones jump and vibrate considerably when brought into contact with their driving rolls and the cones are driven at uneven surface speeds, due to the varying driving contact of the driving roll along the cone. These defects cause the yarn to wind badly and to run out of true until a substantial amount of yarn has been wound onto the cone.

The object of my invention is to overcome these objectionable features by providing the winding surface of the cone with a driving element, such for instance as an exterior circumferential bead adapted to be engaged by the driving roll when the cop is brought into winding position, the weighted cone holder serving to cause the said bead to be quickly ironed out sufficiently by the winding roll to bring the same into concentric relationship to the axis of rotation of the cone and thus ensuring the even driving of the cone.

Practical embodiments of my invention are represented in the accompanying drawings, in which—

Fig. 1 represents a cop cone made of paper with my invention applied to its winding surface in the form of a circumferential exterior embossed bead, the cone being shown in its operative relationship to the driving roll.

Fig. 2 represents a similar view showing a somewhat warped cop cone in longitudinal central section.

Fig. 3 represents a similar view showing in longitudinal central section a cop cone in which the wall of one side is thicker than on the other side.

Fig. 4 represents a detail section showing the exterior circumferential bead as an enlargement of the wall of the cone and integral therewith.

Fig. 5 represents a similar view showing a separate ring secured in position around the winding surface of the cone to form the exterior circumferential bead.

The cop cone driving roll is denoted by 1 and its shaft by 2. The weighted cop cone holder is denoted by 3. The cop cone 4 is herein shown as made of paper.

In the embodiments shown in Figs. 1, 2 and 3 the walls of the cop cone are pressed outwardly to form an exterior circumferential embossed bead 5 located a distance from the base of the cone and outstanding slightly beyond the winding surface of the cone in position to be engaged by the driving roll 1 during the beginning of the winding operation.

In the embodiment represented in Fig. 4, the exterior circumferential bead 6 is shown as an enlargement of the body of the cone and integral therewith.

In the embodiment represented in Fig. 5, a separate ring 7 is secured in position around the cone to form the exterior circumferential bead.

As the winding operation starts, the weighted cone holder 3 will press the exterior circumferential bead on the cone against the driving roll sufficiently to cause the driving roll to iron out the bead to a greater or lesser extent to bring the same into concentric relationship to the axis of rotation of the cone and thus immediately stop the cone from jumping or vibrating and also ensuring the even winding of the yarn onto the cone from the beginning of the winding operation, irrespective of whether the winding surface of the cone is somewhat irregular, due to the varying thickness of walls, warping or other causes.

For the proper winding of the cop it is very important that the cone be driven at all times at an even speed. For instance if the cone has a flat surface it is impossible to drive it an even speed for the driving roll will engage the cone at so many different points. By providing the cone with the exterior circumferential driving bead, a positive point of driving contact between it and the driving roll is provided until the yarn is wound on the cop beyond the said contact, the winding by this time being leveled up and the cone running true.

It is evident that the forms illustrated herein are only a few of the many different forms which my invention might take;

hence, I do not wish to limit myself to the particular embodiments herein shown and described, but

What I claim is:—

- 5 1. A cop cone provided with a circumferential driving element outstanding from its winding surface.
2. A cop cone provided with an exterior circumferential driving bead.
- 10 3. A cop cone provided with an exterior circumferential driving bead located a fixed distance from the base of the cone.
- 15 4. A cop cone having an exterior circumferential driving bead formed integral therewith.
- 15 5. A cop cone having an exterior embossed circumferential driving bead.

6. A device for ensuring the even driving of a cop cone comprising an exterior circumferential driving bead on the winding 20 surface of the cone, and a driving roll arranged to engage said bead.

7. A device for ensuring the even driving of a cop cone comprising an exterior circumferential driving bead on the winding 25 surface of the cone, and a driving roll arranged to iron out said bead sufficiently to bring it into concentric relationship to the axis of rotation of the cop.

In testimony, that I claim the foregoing 30 as my invention, I have signed my name this 22nd day of December, 1922.

JOHN O. McKEAN.
